UNITED STATES PATENT OFFICE.

EDITH C. JENSEN, OF SAN FRANCISCO, CALIFORNIA.

STAGE GARMENT.

Application filed November 23, 1927. Serial No. 235,164.

My present invention relates to wearing apparel and more particularly to a garment for stage and amusement affairs.

An object of my invention is to provide a garment of the above type which is capable of rearrangement so as to present the wearer in different costumes.

A further object of my invention is to provide in a garment of the above type, means whereby changes in the appearance of the garment can be instantaneously made in full view of the audience.

Another object of my invention is to provide a garment of the above type wherein at least two changes of appearance can be produced with the parts so arranged that when one of the garments is exposed to view, the other will be completely concealed.

In costuming for stage appearance and particularly in the case of a single performer such as in a dancing act or the like, it is essential that, if changes of costume are to be made, they be made in a minimum of time and because of this fact it has been difficult for a single performer to make many changes in costume because of the time consumed therein which necessitates their absence from the stage.

In order to overcome the above disadvantage, I have provided a garment which is capable of producing a substantially instantaneous change in appearance, either in the presence of the audience or out of their view so that practically no time is consumed in accomplishing the transformation and, in fact, by proper manipulation I have found it possible to make a change in full view of the audience which produces a very entertaining effect, as when properly manipulated in this fashion the change is carried out in what would be termed in stage parlance a "mysterious manner".

For a better understanding of my invention, reference should be had to the accompanying drawing in which I have shown a garment suitable for a dancing act or the like, in which I have provided three distinct changes of costume. In these drawings—

Fig. 1 shows a dancing girl clothed in a garment in accordance with my invention with the parts thereof broken away to expose portions of the different changes of costume, and

Fig. 2 is a fragmentary view of the garment alone showing the various positions assumed by the parts thereof.

In Fig. 1 my improved garment is shown as comprising two parts which make it possible to produce three distinct changes of appearance which I shall designate by the letters A, B, and C, the appearance A being the first exposed to view, and B and C following in their order thereafter. The costume A has a waist portion 10 and a skirt portion 11; the costume B has a waist portion 12 and a skirt portion 13; and the costume C has a waist portion 14 and a skirt portion 15. The skirt portions and waist portions above referred to are all secured to a common belt portion 16 and each waist portion is provided with detachable fasteners 17 at the sides thereof below the arms of the wearer and similar fasteners 18 at the shoulders thereof. In order that the fasteners 18 may be conveniently released, I have provided in one modification of my invention a tie or braid 19 which extends down to a point adjacent the side fasteners so that the operator may, if desired, release the shoulder strap from this point by merely pulling on the braid 19. This feature, however, is not a necessary element of my invention as it is conceivable that any unusual pull upon the shoulder portions will be sufficient to release the fasteners 18. It should be understood that each of the waist portions are provided with fasteners of the above character.

In Fig. 2, I have shown the relative positions of the skirt portions and waist portions as they arrange themselves when released to their downward position below the belt portion 16. From this figure, it will be seen that the skirt 11 of the costume A hangs down adjacent the body of the wearer and its corresponding waist portion 10, when released, falls downwardly thereover and is covered by the skirt portion 13 of the costume B, the waist portion 12 of costume B, when released, falling downwardly over the skirt portion 13 where it is concealed by the skirt portion 15 of the costume C. The waist portion 14 of the costume C will be permanently secured to the body of the wearer and will not be provided with the releasable fasteners 17 and 18 previously referred to. At the extreme right of this figure of the drawing the skirt 13 is shown in section as rolled or folded and held upwardly in this position by the waist 10 of the costume A and the skirt portion 15 is partially shown in elevation in its folded position as it is arranged between the waist portions 12 and 14. From the drawings it will be seen that the waist

portions and their respective shoulder portions are so proportioned that each succeeding under-garment portion will be completely concealed by the portion thereabove.

- 5 From the above it will be seen that I have produced a garment which is capable of producing changes of appearance thereof which can be produced in full view of the audience and in a perfectly presentable manner. In
10 an act involving the use of a garment of this type the operator, after having first properly donned the garment, will appear in costume A and, after having performed or otherwise appeared, will then surreptitiously release
15 the fasteners of the outermost waist portion and, by pirouetting or maneuvering in some such fashion, permit the outermost waist portion to fall downwardly and thereby release the skirt portion concealed thereby so as
20 to present to view the next underlying waist portion and a skirt portion corresponding thereto. In the construction of a garment of this type, the designs of the various garments will be such that a considerable contrast therein will appear so as to make the change as noticeable as possible.

While I have shown the preferred form of my invention as now known to me, it is to be understood that various changes may be made
30 in its construction without departing from the spirit of the invention as defined in the appended claims.

Having thus described my invention, what

I claim and desire to secure by Letters Patent is—

35

1. A garment of the character described comprising a belt portion, a plurality of waist portions, a plurality of skirt portions superimposed upon each other and secured to said belt portion, said waist portions being alternately disposed with said skirt portions and also secured to said belt portion, whereby only one waist portion and a corresponding skirt portion can be exposed at one time,

40

2. A garment of the character described comprising a plurality of skirt portions, a single belt portion, and a plurality of waist portions alternately arranged with said skirt portions by the said belt portion and adapted to each conceal a skirt portion corresponding in design to the next underlying waist portion.

45

3. A garment of the character described comprising a plurality of skirt portions, a belt portion, and a plurality of waist portions alternately arranged and secured with said skirt portions to said belt portion and adapted to each conceal a skirt portion corresponding in design to the next underlying waist portion, said waist portions being so arranged that when released they will expose a concealed skirt and then be concealed by the released skirt portion when the latter has assumed its normal position.
